POWER LIMITER FOR DISCHARGE TUBES

Walter van B. Roberts, Princeton, N. J., assignor
to Radio Corporation of America, a corpora-
tion of Delaware

Application April 28, 1942, Serial No. 440,883

4 Claims. (Cl. 250—27)

This invention relates to power supply circuits for amplifier tubes, especially tubes working at low efficiency such as class B stages or frequency multipliers, and provides means for limiting the power input to such tubes to a value within the safe dissipation rating of said tubes.

The object of the invention is to provide a power supply for low and medium power stages such that the power input to the stage cannot exceed a predetermined safe value regardless of any possible type of circuit misadjustment, while at the same time permitting the power input to attain a value comparable with the maximum allowable in the presence of proper circuit adjustments. The invention may be applied to high power stages also whenever the dissipation of power in the supply circuits is not objectionable.

In the case of a purely dissipative load—that is, a load in which all the input power is dissipated in heat, the power input may be limited to a desired value under all conditions of load variation while providing a normal input in the case of normal load resistance by employing the arrangement described in my United States Patent No. 2,218,925 and also in my article entitled "Foolproof screen feed," published in "QST" for October 1940. In the case of an amplifier or frequency multiplier tube, however, conditions are somewhat different because not all of the input power is dissipated in the tube when the circuits are correctly adjusted.

My invention will now be described in more detail, reference being made to the accompanying drawing, in which:

Fig. 1 shows diagrammatically a circuit arrangement which exemplifies my invention;

Fig. 2 shows a modification of the circuit arrangement which also is comprehended in my invention; and

Fig. 3 shows another modification of my invention which is particularly suited to the requirements of a frequency multiplier.

In Fig. 1, I show a conventional discharge tube circuit arrangement including a triode discharge tube 1, the output circuit of which includes the direct current source 3, a resistor R, and a parallel-tuned circuit comprising inductance 5 and capacitor 7. The cathode of the tube 1 and also the negative terminal of the source 3 may be grounded if desired. In shunt with the source 3, I preferably insert a by-pass capacitor 9.

The circuit arrangement of Fig. 2 is similar to that of Fig. 1 with the exception that the output circuit for the tube 1 includes an additional resistor 2 connected between the cathode and

ground. This resistor is preferably shunted by a by-pass condenser 4.

Fig. 1 shows an amplifier or multiplier stage having a resistance R in series with the power supply voltage. A series resistance such as here shown is not of itself new and such resistances have been commonly used during preliminary adjustments of circuits for safeguarding the tube. However, once the circuit is adjusted the resistance has always been removed as it was found to seriously reduce the output of the stage. In accordance with the present invention, however, this resistance is left in for normal operation as it will be shown that by suitably increasing the voltage of the plate supply source above its normal value and by properly choosing the value of resistance R the output of the stage may be maintained sufficiently near its normal value for many purposes while retaining the important advantage of safeguarding the tube against all contingencies at all times.

The operation and adjustment of the circuit of the invention may best be understood by reference to a mathematical analysis. Referring to Fig. 1 let us suppose that in the absence of resistor R the normal plate supply voltage is E, the normal power input is P, and the dissipation is W. In accordance with the invention the resistance R is now inserted and the plate supply voltage is raised to a value mE where m is a coefficient whose value will be determined later.

For the sake of generality, let us suppose that during various circuit misadjustments the effective plate circuit resistance of the tube may take on any value from zero to infinity. It may readily be demonstrated that the maximum input to the tube occurs when the effective tube resistance is equal to the resistance R and this maximum possible input is

$$40 \quad \frac{(mE)^2}{4R}$$

Hence if it is desired that the tube input should never exceed W, we may equate

$$45 \quad \frac{(mE)^2}{4R} = W$$

to W and thus by solving this equation for R, determine that the required value of R is

$$50 \quad \frac{(mE)^2}{4W}$$

When the circuits are properly adjusted the normal effective tube resistance is E^2/P . Hence the current supplied to the tube is obtained by dividing the voltage mE by the sum of the nor-

mal effective tube resistance E^2/P and the series resistance $\frac{1}{4}E^2/W$. The power input to the tube is then obtained by squaring the current and multiplying by the normal effective tube resistance. After simplification the power input may be expressed as $P = (1/m + \frac{1}{4}mP/W)^2$. In this expression the quantity m is still undetermined. Since we should make the power input as large as possible the expression is maximized with respect to m whereby it is found that the expression is maximum when m is equal to $\sqrt{4W/P}$ and when this value of m is employed the power input becomes equal to W . At the same time the value of the series resistance becomes equal to the normal effective tube resistance E^2/P .

Summarizing the results of the foregoing analysis it may be said that:

1. To obtain maximum output in the presence of correct circuit adjustments while at the same time providing an upper limit of input equal to the dissipation of W of the tube, insert series resistance E^2/P and raise the plate supply voltage to $E\sqrt{4W/P}$.

2. With the above provisions, the stage output is reduced from the normal value (that is, the value obtained prior to an installation of the safeguarding arrangements) in the ratio W/P .

3. From item 2 above it is seen that the reduction in output resulting from the use of the safeguarding circuit of the present invention is less serious as the normal efficiency of the stage is lower, so that the circuit is of particular advantage in low efficiency stages such as class B or linear radio frequency amplifiers or frequency multipliers especially triplers, quadruplers, etc., or in low power stages where the power loss in the series resistor is not important and where the reduced output is still sufficient. Fig. 3 shows a preferred circuit arrangement for use in frequency multipliers.

Referring now to Fig. 2, a series resistance 2 is shown connected between cathode and ground to provide bias for the stage. Preferably this resistance is made sufficient to provide the entire bias required. In the case of frequency multipliers where a high bias is desirable, it will usually be preferable to put the entire series resistance R between cathode and ground, as shown in Fig. 3. It might be thought that when the series resistance is arranged to provide high bias a lower total value of resistance would suffice for safeguarding the tube. This may be true in the case of the commoner types of misadjustment of the stage, but to safeguard against the possibility of the grid becoming positive the total resistance must still be of the value derived above.

While I have obtained conditions under which the maximum possible power output of the stage is preserved together with complete safeguarding, it will be appreciated that these conditions may be departed from somewhat in case maximum power output is not required or in case safeguarding against the commoner types of circuit misadjustment or lack of excitation is all that is

needed. Therefore, I do not believe my invention to be limited to the optimum adjustments of the circuit thereof, but only in accordance with the following claims.

5. I claim:

1. In a class B discharge tube stage, a tube and a source of anode potential therefor, a resistance connected in series with said source and said tube, said resistance being substantially equal to the impedance of said tube, thereby to limit the input power to said tube to a safe value and said source having sufficient voltage to cause the normal input to said tube to be substantially equal to said limiting value.

15. 2. A power limiting device for a class B amplifier, comprising a discharge tube, an output circuit connected between its anode and its cathode, said circuit including a resistance in series with a direct current source, said resistor being substantially equal to the impedance of said tube, thereby comprising means for obtaining maximum output from said tube in the presence of correct circuit adjustments, while at the same time providing an upper limit of power input 25 equal to the permissible dissipation within the tube.

3. In a frequency multiplier circuit arrangement, a discharge tube having at least a cathode and an anode and having a maximum safe wattage dissipation factor W , an output circuit connected between the cathode and anode, a direct current source having an adjusted terminal voltage equal to $E\sqrt{4W/P}$ in said output circuit and means in said output circuit for limiting the input power to the maximum safe dissipation of watts within said tube in the presence of either abnormal or normal circuit adjustments for said tube, said means including a resistor the value of which is equal to

$$\frac{E^2}{P}$$

where P represents the normal power input for said tube and E represents the normal voltage of said source that would be required in the absence of said resistor.

4. In a discharge tube circuit arrangement such that its anode potential is delivered by a given source through a suitable resistor, the 50 method of obtaining a maximum output from said tube in the presence of correct circuit adjustments, while at the same time providing an upper limit of input equal to the dissipation W within the tube, measured in terms of watts 55 which consists in assigning a value of

$$\frac{E^2}{P}$$

to said resistor and a value of $E\sqrt{4W/P}$ to said source, where P represents the normal power input for said tube and E represents the normal voltage of said source that would be required in the absence of said resistor.
